CROSS PARTITION

William S. Henderson, Monroe, Mich., assignor to Consolidated Packaging Corporation, Monroe, Mich., a corporation of Michigan

Filed Jan. 20, 1964, Ser. No. 338,730

2 Claims. (Cl. 229—15)

This invention relates to carton partitions and more particularly to an improved cross partition for the interior of a carton which serves to define article receiving and separating pockets therefor.

An object of the present invention is to provide an economical partition or spacer which may be made of inexpensive material easily and quickly produced by a low cost process on inexpensive machinery.

Another object of the invention is to produce a collapsible multipart partition from a single blank of material subsequently separated into its several parts.

Another object of the invention is to provide a partition for dividing a carton into a plurality of sections or compartments including, for example, four compartments of substantially equal size.

Generally speaking the partition comprises at least two pair of panels formed from a single sheet of paperboard, such as a rectangular or square blank, which is cut, scored, folded, glued and separated into at least two sections. Each of these sections or pair of panels is provided with complementary tabs and alternate scores adjacent their longitudinal intermediate or their center lines, and is arranged so that the tabs of one section overlie the scores of the opposite section. Since there is adhesive between the tabs of each section and the opposite section, when each section is bent along its intermediate or center line, such as at a right angle, to form the separate panels, the tabs of one section will be secured to the opposite section and the partition will assume the shape of a cross.

The above mentioned and other features and objects of this invention and the manner of attaining them will become more apparent and the invention itself will be understood best by reference to the following description of an embodiment of the invention taken in conjunction with the accompanying drawing, wherein:

FIG. 1 is a plan view of a rectangular blank scored, cut and provided with a glue strip to produce the partition of the present invention;

FIG. 2 is a plan view of the blank of FIG. 1 collapsed or folded back upon itself with the glue tabs of each section secured to the opposite section;

FIG. 3 is a top plan view of the erected partition in a square carton to divide the same into equal parts;

FIG. 4 is a fragmentary perspective view of the erected partition;

FIG. 5 is a sectional detail view taken substantially on line V—V of FIG. 2 but with the sections spread;

FIG. 6 is a sectional detail view similar to FIG. 5 but on line VI—VI of FIG. 2; and

FIG. 7 is an end view of the collapsed, folded and glued blank of FIG. 2 illustrating one means for severing the same into two parts for subsequent erection.

Referring to the drawings, and particularly to FIGS. 1 and 2 thereof, the partition or divider 15 shown in FIGS. 3 and 4 may be made from a rectangular blank 20 of fibrous sheet material, such as paperboard. The blank 20 may be scored and cut as shown in FIG. 1, including a cut or tear score or line of perforations 22 between the longitudinal edges of the blank such as along the center line, which line 22 is preferably more cut than connected and also serves as a fold line for dividing the blank 20 into two panel sections or panel pairs 24 and 26. Between the longitudinal edges of section 24 or outwardly from perforated line 22, there may be provided alternate fold

2

scores 28 and cuts 30, the cuts 30 being disposed to one side of the line of the fold scores 28, as illustrated. Section 26 is also provided between its longitudinal edges with alternate scores 36 and cuts 38, the cuts 38 being arranged on the opposite side of the line of the scores 36 in section 26 from the cuts 30 in section 24.

Cuts 30 comprise spaced longitudinal portions 32 from which obtuse angular divergent portions 34 extend toward and connect with scores 28. Cuts 38 may also include spaced longitudinal portions 40 at the opposite ends of which are opposed V-shaped portions 42 one leg 43 of each of which terminates at the scores 36, which legs 43 also match with the angularity of divergent cuts 34 of cuts 30 when sections 24 and 26 are folded together along perforated line 22 as shown in FIG. 2. By making these cuts 34, 42 and 43 at obtuse angles instead of perpendicular to the score lines 28 and 36, the releasing and nesting of the tabs 46 and 47 are facilitated in setting up or collapsing the partition 15.

Prior to folding the sections 24 and 26 together, as in FIG. 2, an adhesive 45 may be applied along the alternate scores and cuts of either or both sections 24 or 26, as shown in FIGS. 1 and 2, such adhesive 45 being applied along a strip not wider than the width of the tabs 46 or 47 formed by the cuts 30 or 38, respectively. Due to the alternate arrangement of the scores 28 and cuts 30 in sections 24 and the scores 36 and cuts 38 in section 26, the tabs 46 will overlap the scores 36 and tabs 47 will overlap the scores 28 when the sections 24 and 26 overlie each other as shown in FIG. 2. Accordingly, tabs 46 of section 24 will be secured to section 26 and tabs 47 will be secured to section 24 along glue strip 45.

The scores 28 and 36 also serve as fold lines forming a median line along which not only are sections 24 and 26 secured together, but also permits each section to form an angle such as a right angle by bending the adjacent panels outwardly which forms a partition of generally cross-shape as particularly shown in FIGS. 3, 4, 5 and 6. Such a partition may be used to divide an elongated carton 50 into four equal sections, which sections may serve to separate stacks of ice-cream cones or paper cups, for example. Such an arrangement provides a plurality of pockets in carton 50 for preventing contact between and resultant damage to such or other fragile articles.

In producing the collapsed cross-partition of this invention, the blank with the cuts and score lines can be formed in one operation, then a continuous strip of adhesive 45 may be applied thereto and the panel pairs 24 and 26 folded together ready for shipment, the perforated or alternate cut and spaced line 22 being such that it can be severed or torn apart easily upon assembly by the consumer. Preferably, however, the sections 24 and 26 are separated along line 22 in the gluing and folding machine by means of a knife or sword means 52 such as shown in FIG. 7.

While there is described above the principles of this invention in connection with specific apparatus, it is to be clearly understood that this description is made only by way of example and not as a limitation to the scope of this invention.

What is claimed is:

1. A partition for dividing a carton into a plurality of sections, said partition being formed from a rectangular blank divided longitudinally into two sections by a perforated score line, each section being further provided with intermediate longitudinal alternate cuts and scores forming spaced and staggered glue tabs, and means to secure the tabs of each section to the opposite section so that by separating said sections along said perforated score line and bending each section at an angle a cross partition is produced.

2. A method of making from a sheet of fibrous material a multi-panel cross partition for a carton to divide said carton into at least four parts, the steps comprising:

- (a) cutting a rectangular blank as long as said partition and as wide as all four panels of said partition, 5
- (b) perforating said blank longitudinally along a line between its two side edges so that it can be later separated into two pairs of panels,
- (c) alternately scoring and off-set cutting tabs along a line between the side edges of each of said panel pairs to define said panels, said scoring on one panel pair being directly opposite the off-set cuttings on the other panel pair, said off-set cuttings forming flaps,
- (d) applying adhesive along and between said flaps on 10 at least one of said panel pairs,

- (e) folding said panel pairs together along said perforated line to adhere all of said flaps to a portion of an adjacent panel,
- (f) separating the adjacent panels along said perforated line, and
- (g) folding said panel pairs along their score lines to separate said panels to form said cross-partition with the central axis of said partition along said folds.
